APPARATUS FOR FILLING BAGS
Billy J. Scott, Borger, Tex., assignor to Phillips Petroleum
Company, a corporation of Delaware
Filed Oct. 14, 1960, Ser. No. 62,691
4 Claims. (Cl. 177—80)

This invention relates to improved apparatus for filling porous containers with powdered materials.

U.S. Patent 2,799,465, issued July 16, 1957, to Carter discloses a bag filling apparatus with which this invention is concerned. The machine of said patent employs a reduced pressure or partial vacuum within a bag enclosing shroud to draw and compact finely divided material into the bag. After a small portion of bag capacity is filled with the powdered material in this manner, the pores of the bag become at least partially plugged with the material. To overcome this, a vacuum line to the shroud is closed and air is vented into the shroud thru a valve so as to partially restore the pressure in the shroud and cause air to enter the bag, thereby removing powdered material from the wall of the bag and unplugging the pores or interstices in the wall so that incremental filling of the bag can be continued by repeating the cycle of reducing the pressure in the shroud, injecting material into the bag, and again cutting off the flow of material and increasing the pressure in the shroud.

An apparatus made in accordance with the Carter patent, bearing the label, "Serial No. 217, Model VB," was obtained from Carter Engineering Company, Danville, Illinois. This machine was used for a substantial period in the packaging of loose carbon black and proved very satisfactory except that the vacuum control (device 165 in FIGURE 6 of the drawing) failed to operate and open the filling valve (valve 133 of FIGURE 2) in the conduit leading from the feed hopper to the filling nozzle. Vacuum control device 165 senses pressure in the shroud 40 thru a conduit (not shown) leading from the shroud to the control and it was found that, after extended use, the conduit became plugged with carbon black so that the control device became inoperable in that it could not sense the changes in pressure within the shroud.

An improved control arrangement for the apparatus was devised and the apparatus, revised in accordance with the control arrangement of the invention, has worked continuously over extended periods without any operating difficulties and shutdowns caused by failure of the controls. The control arrangement of the invention is described herein.

Accordingly, the principal object of the invention is to provide an improved apparatus for incremental filling of porous containers with powdered materials. Another object is to improve the control arrangement of the bag filling apparatus of above-identified patent. Other objects of the invention will become apparent upon consideration of the accompanying disclosure.

The invention will be best understood by reference to the accompanying schematic drawing of which FIGURE 1 is an elevation of a bag filling machine in accordance with the invention; FIGURE 2 is a plan view taken on the line 2—2 of FIGURE 1; and FIGURE 3 is a view of the circuitry and controls employed in the automatic operation of the filling machine.

Referring to FIGURES 1 and 2, a shroud 10 is suspended from a weighing device 12 which is supported from a frame (not shown). Support rod 14 is pivoted on beam 16 which is supported by fulcrum 18. Weight 20 is adjustable along beam 16 to control the total filling weight of the bag. Upon filling of the bag to the predetermined weight, beam 16 actuates weight switch WS so as to open

2

its contacts which are in an electrical circuit designed to terminate the filling cycle.

Filling nozzle or spout 24 extends into the upper end of shroud 10 and is provided with pneumatic sealing device 25 including seals 26 and 27 for holding a bag on the filling spout in sealed relation with the mouth of the bag. Nozzle 24 connects by conduit means 28 with a supply hopper 30. Pneumatic material-fill-valve 32 in conduit 28 controls the flow of powdered material into the feed nozzle. A vacuum line 34 containing pneumatic valve 36 connects with the shroud and with a vacuum source (not shown) for reducing the pressure therein. An air inlet or relief line 38 connects with the shroud and is provided with pneumatic relief valves 40 for decreasing the vacuum in the shroud.

Shroud 10 is divided diagonally into two sections which are sealed along plane 42. Section 43 is relatively fixed and section 44 is pivoted at hinge 46 so that section 44 functions as the door of the shroud. An arm 48 is fixed to door 44 and is pivotally connected with pneumatic opening and closing device 50 which is pivotally connected with arm 52. Door switch DS closes contacts in an electrical circuit upon closing of door 44 to start the filling sequence as described hereinafter.

25 The device thus far described is substantially disclosed in said patent. In addition to the apparatus described herein, the Carter device includes a vent valve 134 which has been found to be unnecessary in filling a porous bag with powdered material. This valve is intended to aid in inflating the bag after insertion on the filling spout and after application of vacuum to the shroud. However, since a bag is partially filled with air when it is placed on the filling spout, the evacuation of air from the shroud outside of the bag adequately expands the bag for the incremental filling which follows.

The controls for operating the device thru a complete filling sequence or cycle are shown in FIGURE 3. Leads L-1 and L-2 connect with a suitable power source such as a 110 volt 60 cycle alternating current source. The contacts of WS are normally closed and are not opened until the weight of the material within the bag being filled causes the weighing device 12 to open the contacts of the switch. Contacts RH₁ are also normally closed. All other switches and relay contacts are shown in their open state as they exist prior to commencing of the automatic filling cycle.

50 A start push button 60 which is normally open and a normally closed stop button 62 are connected in series with the contacts WS and the coil of a relay RA. Contacts RA₁ of relay RA are connected in shunt across start button 60 so as to form a holding circuit for relay RA, once the contacts of push button 60 have been momentarily closed to energize the relay. Contacts RA₂ of relay RA are connected across the leads of the power source in series with contacts WS and the coils of solenoids SA, SB, SC, and SD. Thus, when contacts RA₂ are closed, the solenoids are energized thru contacts WS.

Solenoids SA and SB are connected to actuate separate pneumatic 3-way valves 64 and 66, respectively, which are operable to couple alternately pressurized fluid or atmospheric pressure with pneumatic door actuator 50. As described hereinbefore, door actuator 50 is positioned to effect opening and closing of shroud door 44. In the relation shown in FIGURE 3, the valves controlled by solenoids SA and SB are disposed to retain the door actuator in its fully opened position. Upon energization of solenoids SA and SB, the valves 64 and 66 move to couple pressure to the left side of the actuator piston and vent the right side of the cylinder to atmosphere. This action closes door 44 for the successive steps of the filling sequence.

Solenoids SC and SD are connected to actuate pneumatic 3-way valves 68 and 70, respectively, so as to either pressurize filling spout seal mechanism 25 (separate seals 26 and 27) or depressurize the same by venting the seals to atmosphere and releasing the clamping action thereof. As shown, the seals are depressurized.

As pneumatic actuator 50 closes the shroud door 44 as the result of energization of solenoids SA and SB, door switch DS is closed so that the contacts are connected in series with the operating coil of relay RB forming a circuit from L-2 thru WS, switches 62 and DS, and relay RB to L-1. One pair of contacts RB₁ of relay RB are connected in shunt around switch DS to form a holding circuit for relay RB.

Upon energization of relay RB, contacts RB₂ are closed so as to start timer 72. Timer 72 is connected in series with contacts RB₂ across the power source. This timer is operable to energize relay RC after a short period such as 1 to 3 seconds. This timer may be of any suitable construction but is preferably an electronic timer and is provided with a dial 74 which can be set for the time delay before energizing relay RC. Contacts RC₁ of relay RC are locking contacts which when closed by energization of relay RC remain locked in closed position until unlocked by relay RH, described hereinafter. Closing of contacts RC₁ establishes a complete circuit from L-2 thru WS, RC₁, and solenoids SF and SG to L-1. This circuit energizes solenoids SF and SG which open vacuum valve 36 and close the relief valve 40, respectively so as to reduce the pressure in shroud 10 for the first incremental filling.

When circuit is established thru contacts RC₁ a circuit is also established thru timer 76 which is provided with dial 78 for adjusting the time delay of this timer in actuating relay RH. The time delay is regulated so as to permit the predetermined reduction of pressure in the shroud before opening fill valve 32 for incremental filling of the bag. Upon actuation of relay RH contacts RH₁ are opened to stop timer 72, and contacts RH₂ are closed to energize solenoid SH which opens the material fill valve 32. After a selected time to provide the desired filling increment, timer 76 de-energizes relay RH so that contacts RC₁ are unlocked and contacts RH₁ are released to again close and make contact to start timer 72. This action again energizes relay RC and closes contacts RC₁ to repeat the steps of the incremental filling cycle.

The time delay between unlocking of contacts RC₁ and re-energizing relay RC should be very short for most efficient operation so as to permit only partial re-establishment of atmospheric pressure in the shroud. This partial restoration of pressure within the shroud causes flow of air thru the walls of the bag so as to remove powdered material from the pores and the inside wall of the bag above the filled level. This allows air within the bag to be displaced and sucked thru the bag wall during the ensuing evacuating step resulting from energizing relay RC and closing of contacts RC₁ so as to energize solenoids SF and SG.

The setting of timer 76 so as to regulate the period during which current is passed thru relay RH to maintain contacts RH₂ closed, determines the fill period or the time during which valve 32 is open. This period depends upon the regulation of the aforesaid time interval and controls the size of the increment of carbon black or other powdered material which is delivered to the bag during each cycle of successive operation of timer 72, relay RC, timer 76, and relay RH. Timer 72 is stopped and reset each time relay RH opens contacts RH₁. Timer 76 resets itself upon de-energizing relay RH and unlocking contacts RC₁.

Valves 32, 36, and 40 are conventional pneumatically operated diaphragm valves. Opening and closing of this type valve is effected by regulating the flow of pressurized fluid (air) to one side of the diaphragm within the valve.

Pressure on the diaphragm of the valve maintains the valve in closed position whereas release of pressure or application of vacuum opens the valve.

From the foregoing disclosure it can be seen that the controls of the invention in combination with the disclosed structure provide a positive time cycle of automatically operating of three valves controlling the pressure reduction in the shroud (valves 36 and 40 and the introduction of powdered material to the filling spout (valve 32). The system of the invention avoids any possibility of plugging of the vacuum line from the shroud to vacuum control instrument 165 of the Carter device by completely eliminating this control and its associated conduit. The invention also eliminates other apparatus elements, such as relays with their associated contact points, and it simplifies the circuitry required for automatic operation of the bag filler.

Certain modifications of the invention will become apparent to those skilled in the art and the illustrative details disclosed are not to be construed as imposing unnecessary limitations on the invention.

I claim:

1. Apparatus for incremental filling of a bag with powdered material, comprising in combination, a shroud substantially sealable to the atmosphere; a filling spout extending into said shroud sealed therewith and provided with means for sealing to the mouth of a bag; a supply vessel connected by a delivery conduit with said spout; a first valve in said delivery conduit; a gas inlet to said shroud; a second valve in said gas inlet; a vacuum line leading into said shroud; a third valve in said vacuum line; first means including a first electrical circuit for substantially simultaneously opening and holding said third valve open and closing and holding said second valve closed for a selected time interval; second means, comprising a second electrical circuit and a first timer therein actuated by said first means after a short time interval to effect pressure reduction in said shroud, for opening and holding said first valve open while said first means is functioning to hold said second and third valves and maintain said pressure reduction, said second means functioning for a short time interval before closing said first valve and reversing said second and third valves to prepare for a second cycle of incremental filling.

2. The apparatus of claim 1 wherein said shroud is provided with an access door and said first electrical circuit is energized by a switch mounted on said door so as to close upon closing said door.

3. Apparatus for incremental filling of a porous bag with powdered material, comprising in combination, a shroud sealable to the atmosphere; a filling spout extending into said shroud and sealed therewith; means on said spout for holding the mouth of a bag in filling position in sealed relation thereto; a delivery conduit connected with said spout; a first pneumatic valve in said conduit; a gas inlet to said shroud having a second pneumatic valve therein; a vacuum line connected with said shroud having a third pneumatic valve therein; a first solenoid operated three-way valve connected by a pneumatic line to said first valve; a second solenoid operated three-way valve connected by a pneumatic line to said second valve; a third solenoid operated three-way valve connected by a pneumatic line to said third valve; a first electrical circuit including the solenoids of said second and third three-way valves; a second electrical circuit including a first timer, a first relay actuated by said timer, and normally closed contacts in said second circuit; locking contacts in said first circuit responsive to said first relay for closing the circuit thru said solenoids; a third circuit connected with said first circuit, including a second timer, a second relay actuated by said second timer, and the solenoid of said first three-way valve, said second relay functioning to open said normally closed contacts and stop said first timer when energized and to unlock said locking contacts when de-energized, and said second

timer closing said third circuit thru the solenoid of said first three-way valve after a short predetermined time to start filling.

4. Apparatus for incremental filling of a porous bag with powdered material, comprising in combination, a shroud sealable to the atmosphere and providing a chamber for a bag for filling and an access door for introduction and removal of said bag; a first switch mounted so that closing of said door closes said switch, weighing means supporting said shroud and provided with a second switch for terminating the filling cycle upon introduction of the desired weight to said bag; a feed spout disposed within the upper section of said shroud and provided with means for holding the mouth of a bag in sealed relation therewith for filling; a feed conduit connected with said feed spout having a first valve therein

actuatable to open and close said conduit to flow of feed; an inlet to said shroud having a second valve therein for admitting air to said shroud; a vacuum conduit connected with said shroud having a third valve therein; first means, including a timer, actuatable in response to closing of said first switch for opening said third valve and closing said second valve; second means, including a timer, actuatable by said first means after a predetermined time delay, for opening said first valve for a filling increment, said second means operating to close said first valve after a predetermined short filling period and reverse the positions of said second and third valves.
